ATTORNEY.

UNITED STATES PATENT OFFICE.

NELSON L. TUCK AND WILLIAM W. TUCK, OF BROOKLYN, NEW YORK.

VAPORIZER AND IGNITER FOR OIL-ENGINES.

SPECIFICATION forming part of Letters Patent No. 785,388, dated March 21, 1905.

Application filed July 22, 1903. Renewed February 21, 1905. Serial No. 246,780.

To all whom it may concern:

Be it known that we, NELSON L. TUCK and WILLIAM W. TUCK, citizens of the United States, and residents of Brooklyn, in the county 5 of Kings and State of New York, have invented a certain new and useful Improvement in Vaporizers and Igniters for Oil-Engines, of which the following is a specification.

This invention relates to igniters for internal-combustion engines, the main object of the invention being to provide an igniter of a nature such that it will afford a large heating-surface on which the fuel will be sprayed and then be ignited by the heat developed in the igniter as the mixture or charge is compressed by the piston of the engine after the said igniter once reaches a given temperature and the engine is started and operated a short while by ordinary means, as 15 alcohol-fuel and an ordinary igniter.

To the ends thereof the invention consists of the igniter, arrangements, and combinations of devices hereinafter described, and more particularly pointed out in the appended 20 claims.

The preferred form of the invention is illustrated in the accompanying drawings, forming part hereof, in which—

Figure 1 is a longitudinal sectional view, 30 and Figs. 2 and 3 are surface views of parts shown in section in Fig. 1.

In the drawings the reference *a* marks the cylinder, *b* the inlet or fuel-injector, and *c* a flame or a sparker or electrical igniter. The 35 foregoing are or may be of any suitable or known construction and operation. Suspended from the cylinder-head and between the injector *b* and igniter *c* is the igniter *d*, which more particularly forms part of the subject- 40 matter of the present invention. The igniter *d*, as illustrated in the drawings, comprises three disks *e*, one or more of them being provided with distance fingers, lugs, or pins *f* (baffles) arranged to break up the fuel charge 45 coming in through the injector *b*. Supported below the igniter *d* is a drip pan or catch consisting, preferably, of a plate *g*, having a circular groove *h* arranged in its top face. The igniter *d* and pan *g* may be suspended 50 by one and the same bolt *i*, as shown. The ignition of the charge (hydrocarbon) takes

place at the end of the compression, as the igniter *d* is formed from such material as will take on an igniting temperature during the compression - stroke once it has attained a given temperature through starting the engine by the use of alcohol and igniting by the igniter *c*. Among the materials which may be used for the igniter *d* may be mentioned cast-iron, which possesses the required properties. The fluid hydrocarbon is vaporized by the hot igniter *d* as it strikes thereon and is mixed with air in a known manner, and the igniter fires the charge as the charge is compressed by the piston. (Not shown.)

What is claimed is—

1. An igniter for hydrocarbon-engines, consisting of a plurality of disks or plates between which are arranged a series of spaced separators or baffles, and made of a material having a small specific heat coefficient.

2. An igniter for hydrocarbon-engines, consisting of a plurality of disks or plates between which are arranged a series of spaced separators or baffles, and made of a material having a small specific heat coefficient, combined with a drip-pan arranged below said igniter.

3. An igniter for hydrocarbon-engines, consisting of a plurality of disks or plates between which are arranged a series of spaced separators or baffles, and made of a material having a small specific heat coefficient, combined with a fuel-injector, and an ordinary igniter.

4. An igniter for hydrocarbon-engines consisting of a plurality of parallel separated disks from one or more of which project fingers, lugs, or pins toward the other or others.

5. An igniter for hydrocarbon-engines consisting of parallel horizontal separated disks from the side of one or more of which project fingers, lugs, or pins, in combination with a horizontally-acting injector, and a drip-pan arranged below said igniter.

Signed at New York city, in the county of New York and State of New York, this 21st day of July, A. D. 1903.

NELSON L. TUCK.
WILLIAM W. TUCK.
